(57) **CLAIM**

The ornamental design for an insole for a shoe, as shown and described.

DESCRIPTION

FIG. 1 is a bottom perspective view of a right insole.

FIG. 2 is a bottom perspective view of a left insole.

FIG. 3 is a top perspective view of the right insole.

FIG. 4 is a top perspective view of the left insole.

FIG. 5 is a top side view of the right insole.

FIG. 6 is a top side view of the left insole.

FIG. 7 is a bottom side view of the right insole.

FIG. 8 is a bottom side view of the left insole.

FIG. 9 is a left side view of the right insole.

FIG. 10 is a right side view of the left insole.

FIG. 11 is a right side view of the right insole.

FIG. 12 is a left side view of the left insole.

FIG. 13 is a front side view of the right insole.

FIG. 14 is a front side view of the left insole.

FIG. 15 is a rear side view of the right insole; and,

FIG. 16 is a rear side view of the left insole.

The figures show two embodiments of the insole: a left insole and a right insole. The embodiment of the insole for the left foot is a right-left mirror image of the embodiment of the insole for the right foot.
